UNITED STATES PATENT OFFICE.

FRIEDRICH SOENNECKEN AND EDWARD CHARLES MAGNUS, OF BONN, GERMANY, ASSIGNORS TO THE FIRM OF F. SOENNECKEN, OF BONN, GERMANY.

WINDING ATTACHMENT FOR COPYING-MACHINES.

No. 921,475.

Specification of Letters Patent.

Patented May 11, 1909.

Application filed December 14, 1908. Serial No. 467,394.

To all whom it may concern:

Be it known that we, FRIEDRICH SOENNECKEN, a subject of the King of Prussia, German Emperor, and resident of 1 Kirsch-
5 allee, Bonn-on-the-Rhine, Germany, and ED-
WARD CHARLES MAGNUS, a citizen of the
United States of America, and resident of 5
Jagdweg, Bonn-on-the-Rhine, Germany,
have invented certain new and useful Im-
10 provements in Winding Attachments for
Copying-Machines, of which the following is a
specification.

This invention relates to copying machines
and is directed toward improvements in the
15 means used for collecting the single moist
sheets of copying paper. It has already
been proposed to pass such sheets at short
intervals apart to a roller where the sheets
are wound together with any suitable form
20 of web. In this way the sheets are effi-
ciently dried.

The object of the present invention is to
provide an improved arrangement of wind-
ing-on device for the copying machine.

25 The invention is also directed toward im-
proved details in connection with the wind-
ing-on device.

According to the present invention the
copying paper is as regards operation re-
30 tained in web form until the copying paper
enters the winding roll. This result is ef-
fected by arranging the winding-on roller
below the exit point from the copying ma-
chine and at a distance less than the small-
35 est length of copying sheet. The winding-on
web which is passed to the winding-on roller
is guided over a cylinder arranged above the
winding-on roller so as to form a pocket into
which the moist copying sheets pass. The
40 winding-on web is passed from a supply
roller over the guiding cylinder referred to
above and for the purpose of returning the
web from the winding-on cylinder to the
supply cylinder a ratchet and pawl driving
45 mechanism is employed for the winding-on
roller as hereinafter more particularly de-
scribed.

Referring now to the accompanying draw-
ings Figure 1 is a diagrammatic side eleva-
50 tion of the copying machine provided with
winding-on apparatus according to the pres-
ent invention, Fig. 2 is a plan of the winding-
on apparatus including one of the rollers of
the copying machine, Fig. 3 is a detail view
55 showing the ratchet and pawl driving mech-

anism for the winding-on roller, Fig. 4 is a
sectional elevation of the ratchet and pawl
driving mechanism shown in Fig. 3.

In carrying the invention into effect ac-
cording to the form shown a roll of copying 60
paper 5 is journaled between side frames 6
of the copying machine. From the roll 5
the thin copying paper passes over a guide
roller 7, is suitably moistened and then
passes between the pressing rollers 8 and 9, 65
the lower roller 8 of which is driven by a
handle 10. Over the roller 8 there passes a
tape or the like which also passes between
the rollers 11 and 12. The roller 11 is driven
from the roller 8 through a band 19, and as 70
can be seen from the drawings the driving
pulley of the roller 11 is slightly smaller than
the driving pulley on the roller 8 so that the
roller 11 moves with a slightly greater cir-
cumferential velocity than the roller 8. The 75
paper web passing from the roller 5 is perfo-
rated or otherwise weakened at suitable
places so that when the paper is gripped by
the rollers 11 and 12 which act as dividing
rollers the sheets 13 are separated from the 80
paper web. The sheets 13 which are moist
and heavy after passing over the roller 11 nat-
urally hang easily downward without any
tendency of turning up or crumpling. As
short a distance as possible below the exit 85
point from the rollers 11 and 12, which also
forms the exit point for the sheets from the
copying machine, there is arranged the wind-
ing-on roller 14. The winding-on roller is
supplied with a winding-on web from a roller 90
15 and this web passes over guide cylinders
16 and 17 to the winding-on roller 14. The
guide cylinder 17, which may be in the form
of a cylindrical bar or a rotatable roller as
shown, is arranged above the axis of the 95
roller 14 and guides the winding-on web 18 to
the winding-on roller 14 in such a manner
that a pocket is formed vertically below the
exit point from the copying machine. Into
this pocket the moist single sheets of copying 100
paper pass. The winding-on web 18 may be
made of any absorbent material or may be
composed of wires so as to facilitate the dry-
ing of the sheets on the roller 14. Owing to
the fact that the rollers 11 and 12 move more 105
quickly than the rollers 8 and 9 the sheets
13 are spaced a short distance apart as can
be seen from Fig. 1. The arrangement of
the parts described is such that the supply
roller 15 lies beneath the copying machine as 110

also does the winding-on roller 14. In this way the machine is extremely compact and the sheets are efficiently guided into the winding-on roller 14 without danger of the 5 same being bent or crumpled.

For the purpose of driving the winding-on roller 14 a cross band 20 is passed from the driving roller 8 of the copying machine. The cross band 20 passes over a pulley 21 10 which is fixed on the shaft 22 on which the winding-on roller 14 is loosely journaled. The winding-on roller 14 is driven from the shaft 22 through the ratchet and pawl mechanism illustrated in detail in Figs. 3 and 4. 15 On the shaft 22 there is fixed a ratchet wheel 24 with which ratchet pawls 25 engage. The ratchet pawls 25 are carried by the arms 26 of the winding-on drum or roller 14. Three ratchet pawls 25 are shown and these pawls 20 are provided with pins 27 to which springs 28 are fixed. The springs 28 form connections between the pawls to press the same to the ratchet wheel. Passing loosely over the end of the shaft 22 there is a sleeve 29 to which a 25 disk 30 is attached. The disk 30 is provided with pins 31 which extend laterally so as to come into the plane in which the pawls 25 are arranged. The pins 31 project behind the pawls 25 and when the disk 30 is moved 30 in a counter clockwise direction in Fig. 3 the pins 31 engage against nose pieces 32 formed on the pawls. In this way the pawls are raised from engagement with the ratchet wheel 24. The counter clockwise motion of 35 the disk 30 may be effected by removing the handle 10 from the roller 8 and passing it over the hub 29. A feather 33 on the hub 29 serves the purpose of keying the handle 10 to the hub 29. It will be seen with this arrangement that normally when the machine 40 is in use the winding-on roller 14 is driven through the cross band 20 and for the purpose of unwinding the winding-on web 18 from the roller 14 the handle crank 10 is inserted on the hub 29. The disk 30 is rotated 45 in a counter clockwise direction so that the first part of the motion removes the pawls 25 from engagement with the ratchet wheel 24 and then the pawls 25 act as coupling pieces 50 between the pins 31 and the drum 14 so that the drum is also rotated in a counter clockwise direction. This counter clockwise rotation is communicated to the supply roller 15 by means of a driving cord or the like. 55 The driving member 34 passes over a pulley 35 which carries a pawl 36. The pawl 36 is adapted to engage the teeth of a ratchet wheel 37 fixed to the roller 15. The roller 15 is as can be well understood loosely mounted 60 on its axle or shaft 38. With this arrangement the roller 15 is free to rotate in the direction of unwinding of the winding-on web *i. e.* during normal use of the machine. When, however, the winding-on web is to be 65 unwound from the roller 14 and returned to

the supply roller 15 by the means described above the supply roller 15 is positively driven through the ratchet and pawl 36, 37.

We claim:—

1. A copying machine having in combination with the copying mechanism and means for dividing the moist copies in separate sheets from the paper web, winding means for said moist sheets comprising a winding-on roller arranged below the exit point of the 70 sheets from the copying press, a winding-on web passing to said roller and a guide cylinder arranged above the axle of said winding-on roller and over which the winding-on web passes so as to form a pocket into which the 75 moist sheets pass before they leave the exit point from the copying machine.

2. A copying machine having in combination copying rolls receiving the moist copying paper web dividing rolls moving at a greater 80 circumferential speed than said copying rolls and receiving the web from said rolls, a winding-on roller below said dividing rolls, a winding-on web passing over said winding-on roller and a guide cylinder resting against 85 said winding-on roll above its axle and receiving the divided sheets before said sheets leave the dividing roll.

3. In combination with a copying press, a winding-on roller for the moist sheets, a 90 winding-on web for said roller, a supply roller from which said web passes to the winding-on roller, a shaft driven from the copying machine and on which said winding-on roller is journaled, a ratchet wheel on 100 said shaft, ratchet pawls carried by said winding-on roller and engaging said ratchet wheel for forward driving and means co-operating with the pawls for disengaging the same and returning said supply web to the 105 supply roller.

4. In combination with a copying press, a winding-on roller for the moist copying sheets, a winding-on web for said roller, a supply roller from which said web passes to 110 the winding-on roller, a shaft driven from the copying machine and on which said winding-on roller is journaled, a ratchet wheel on said shaft, ratchet pawls carried by said winding-on roller and engaging said 115 ratchet wheel for forward driving, a disk loosely rotatable on the shaft of the winding-on roller, members carried by said disk and adapted to co-operate with the pawls to first disengage the same and then rotate the 120 winding-on cylinder in the reverse direction.

5. In combination with a copying press, a winding-on roller for the moist copying sheets, a winding-on web for said roller, a supply roller from which said web passes to 125 the winding-on roller, a shaft driven from the copying machine and on which said winding-on roller is journaled, a ratchet wheel on said shaft, ratchet pawls carried by said winding-on roller and engaging said 130

- ratchet wheel for forward driving, a disk loosely rotatable on the shaft of the winding-on roller, members carried by said disk and adapted to coöperate with the pawls to first 5 disengage the same and then rotate the winding-on cylinder in the reverse direction and a ratchet and pawl driving gear for the supply roller, said ratchet and pawl being operative only during reverse rotation.
- 10 6. In a device of the character described the combination on the driven shaft of a ratchet wheel fixed to said shaft, a drum journaled on said shaft a plurality of pawls 15 on said drum and engaging circumferentially with said ratchet wheel, spring connections
- between said pawls to press the same to the ratchet wheel, nose pieces on said pawls, a disk loosely mounted on the shaft and pins carried by said disk and adapted to co-operate with said nose pieces on the pawls 20 to first raise the same from the ratchet wheel and on further rotation of the disk to drive the drum in the reverse direction.

In witness whereof we have hereunto set our hands in the presence of two witnesses. 25

FRIEDRICH SOENNECKEN.

EDWARD CHARLES MAGNUS.
